(57) **CLAIM**

USPC **D13/120**

The ornamental design for a hermaphroditic electrical terminal for an electrical distribution module as shown and described.

(58) **Field of Classification Search**

DESCRIPTION

USPC D13/118-121, 133, 146-149, 154, 184, D13/199

CPC H01R 31/02; H01R 25/162; H01R 13/11
See application file for complete search history.

FIG. 1 is a perspective view of a hermaphroditic electrical terminal for an electrical distribution module showing my new design;

FIG. 2 is a front view thereof;

FIG. 3 is a rear view thereof;

FIG. 4 is a side view thereof;

FIG. 5 is an opposite side view thereof;

FIG. 6 is an end view thereof;

FIG. 7 is an opposite end view thereof;

FIG. 8 is a perspective view of another embodiment of the hermaphroditic electrical terminal for an electrical distribution module showing my new design; and,

FIG. 9 is a front view of the embodiment shown in FIG. 8.
